UNITED STATES PATENT OFFICE.

FLOYD D. STOWE, OF WILMINGTON, DELAWARE, ASSIGNOR TO E. I. DU PONT DE NEUMOURS POWDER COMPANY, OF WILMINGTON, DELAWARE, A CORPORATION OF NEW JERSEY.

PAINTING-MACHINE.

1,239,738.

Specification of Letters Patent. Patented Sept. 11, 1917.

Application filed February 26, 1914. Serial No. 821,232.

To all whom it may concern:

Be it known that I, FLOYD D. Stowe, a citizen of the United States, residing at Wilmington, in the county of New Castle, and in the State of Delaware, have invented a certain new and useful Improvement in Painting-Machines, and do hereby declare that the following is a full, clear, and exact description thereof.

10 My invention relates particularly to a machine adapted to paint detached objects, but it is especially adapted for use in connection with painting kegs, such for example, as powder kegs.

15 The object of my invention is to provide a painting machine in which the painting operation will be carried out entirely automatically. A further object of my invention is to provide an apparatus in which a 20 supply of paint is continually fed to the apparatus in a uniform manner so as to maintain at all times the desired quantity of paint therein. A further object of my invention is to provide such an apparatus in 25 which the object being painted is held at points which will interfere to the least degree with the painting operation.

While my invention is capable of embodiment in many different forms, for the 30 purpose of illustration, I have shown only one form thereof in the accompanying drawings, in which,

35 Figure 1, represents a side elevation of a machine made in accordance with my invention,

Fig. 2 is an end elevation of the same, and

Fig. 3 is an enlarged vertical section of the pumping apparatus used in my invention.

40 In the drawings I have shown a paint tank 1 which is supported upon a main frame 2 constructed in any suitable manner. At the top of the main frame 2 there are located two sets of journal bearings 3 to 45 receive a shaft 4 carrying a pulley 5, driven from any suitable source of power. The shaft 4 at its center has secured thereto a drum 6 which rotates within a semi-cylindrical trough 7 located in the main frame 2.

50 This trough 7 has an outlet opening 8 which is normally closed by screw plug 9. At opposite sides of the drum 6 there are pro-

vided two pairs of yokes or cradles 10, the yokes of a particular pair being located side by side on opposite sides of the drum 6. 55 Each of these yokes has a circular inner surface 11 to receive a keg 12 or other object to be painted, and has also a rearwardly directed extension 13 to assist in removing the painted keg in the manner hereinafter 60 described. One end of the keg 12 is retained in place during the painting operation by a bung 14 which fits in the filling opening of the keg 12 and which is yieldingly pressed against the keg by means of 65 a spring 15 which surrounds a sliding rod 16 attached to the bung. The sliding rod 16 is mounted on an adjustable arm 17 having slots 18 through which pass screws 19 for securing the arm to a right angle bracket 20 attached to the inner face of the drum 6. The other end of the keg 12 is held in place during the painting operation by a lever arm 21 having an adjustable notched head 22 screw threaded thereto and locked in position by a nut 23. The lever arm 21 is pivoted to journal brackets 24 secured to the inner face of the drum 6. A spring 25 attached at one end to an eyelet 26 in the right angle bracket 20 and at the other end to 70 an adjustable eyelet 27 secured to the lever arm 21 by nuts 28, normally tends to move the notched head 22 of the lever arm into engagement with the edge of the keg 12. Prior to the painting operation, however, 75 and after the painting operation has been completed the notched head 22 of the lever arm 21 is disengaged from the end of the keg 12 by a cam surface 29 which co-operates with a roller 30 situated upon one end 80 of the lever arm 21. When the painting operation has been completed the roller 30 coincides with a portion of the cam 29 and at the same time the keg 12 comes into contact with an inclined trip 31 so as to move the filling opening of the keg 12 out of engagement with the bung 14. It will be understood that for the pair of yokes or cradles 10, there is also provided a similar 85 clamping mechanism to that already described in connection with the yokes or cradles 11. During the operation of the painting machine a supply of paint is continually fed thereto in a uniform manner 90 95 100

from the tank 1 by a pump 32. The pump 32 has a piston rod 33 connected to a double cam 34 having upper and lower cam surfaces 35 and 36. The double cam 34 has a vertical slot 37 through which the shaft 4 passes. At its end the shaft 4 carries an outer arm 38 which is provided with a roller 39 to move the double cam 34 upwardly and downwardly by coöperation with the cam surfaces 35 and 36. The shaft 4 also has at its end an inner arm 40 having a circular outer surface 41, the purpose of which is to maintain the piston rod 33 at each end of its path for a sufficient interval of time to permit the pump to receive its charge of paint preparatory to pumping the same into the trough 7. The piston rod 33 is hollow and has a piston 42 on its lower end which operates in a cylinder 43 having an annular outlet opening 44 connected by means of a pipe 45 with the bottom of the tank 1. On the top of the cylinder 43 there is a cylinder head 46 from which an outer tube 47 leads upwardly, surrounding the piston rod 33. The top of the outer tube 47 passes into a housing 48, in such a manner as to extend a short distance above the bottom thereof, the tube 47 being retained in place by nuts 49. The housing 48 has a lateral passage way 49^a, which communicates with the side of the trough 7. Above the end of the outer tube 47 the piston rod 33 has attached thereto a deflector plate 50, so as to deflect the paint flowing from the upper end of the tube 47 downwardly away from outlet openings 51, which are located in the piston rod 33 immediately above the deflector plate 50. The deflector plate 50 is secured in position by a screw 52 which is screwed into a deflector bell 53 attached to the piston rod 33 in any desired manner above the level of the outlet openings 51. In order to keep the paint continually stirred up, I have provided a pair of pivoted stirrers 54, pivotally supported in journal brackets 55 in the interior of the paint tank 1. Each of these stirrers has an upwardly directed arm 56 to each of which there is attached a link 57 pivotally connected to a lever arm 58 on a shaft 59, which is supported in journal brackets 60 above the top of the tank 1. At its end the shaft 59 has a lever arm 61 which is connected by a link 62 to the double cam 34. The paint tank 1 has a filling opening 63 at one end to permit the supply of paint to be replenished.

In the operation of the machine the kegs 12 are placed in the yokes or cradles 10 and 11 as they are moved upwardly to the top of the machine, the kegs being placed in such a position that the filling openings register with the bungs 14. As the kegs pass downwardly the cam surface 29 releases the lever arms 21 so as to cause the springs 25 to move the notched heads 22 into engagement with the edges of the kegs. As the kegs are thus gripped between the bungs 14 and the notched heads 22 they pass downwardly and are submerged in the body of paint present in the trough 7 so as to be completely covered thereby. The kegs are thus carried around on the drum 6 until the painting operation is completed when the rollers 30 on the lever arms 21 come into contact with the cam surface 29, thus releasing the notched heads 22 from engagement with the edges of the kegs, and the kegs are released from engagement with the bungs 14 by coming into contact with the inclined trip 31. The kegs are thus carried up to the upper edge of the trough 7 where a further rotation of the drum 6 causes the rearwardly directed arms 13 on the yokes or cradles 10 and 11 to push the painted kegs over the edge of the trough 7, from which they may be conveyed in any suitable manner to any desired place for the drying of the paint. During the painting operation a supply of paint is continually fed to the trough 7 in a uniform manner by the reciprocation of the piston 42 in the cylinder 43. Upon the upward stroke of the piston rod 33 the piston rod is moved by the contact of the roller 39 with the upper cam surface 35, the cylinder 43 above the piston 42 having been previously supplied with a charge of paint from the tank 1 through the pipe 45 and the annular inlet opening 44. The paint which thus flows into the upper portion of the cylinder 43 is forced upwardly between the outer tube 47 and the piston rod 33 until it flows over the top of the outer tube 47 and through the pipe 49 into the trough 7. The small cross-sectional area of the passageway between the tube 47 and the piston rod 33 as compared with the cross-sectional area of the cylinder 43 causes the paint to readily flow upward in the manner described. When the piston 42 has reached the upper end of its path, it is maintained in this position for an interval of time by the circular surface 41 of the arm 40 in order to permit the paint to completely fill the lower portion of the cylinder 43 beneath the piston 42. Thereafter the roller 39 coöperates with the lower cam surface 36 to move the piston 42 downwardly thereby forcing the paint from the lower portion of the cylinder 43 upwardly through the piston rod 33 and out through the openings 51 and the passageway 49 into the trough 7. The piston is now retained for an interval of time at the lower portion of its path by the circular surface 41 until the paint has had a sufficient interval of time to fill the upper portion of the cylinder 43 above the piston 42. During the operation of the painting machine the paint in the tank 1 is continually stirred up by the stirrers 54 which are operated during the reciprocation by the link 62

which is attached to the double cam 34. When necessary a new supply of paint may be introduced into the tank 1 through the supply opening 63.

5 While I have described my invention above in detail, I wish it to be understood that many changes may be made therein without departing from the spirit of my invention.

10 I claim:

1. In combination, a paint trough, means for submerging in the paint therein kegs to be painted, including rotary clamping devices clamping the keg at the filling opening.

15 2. In combination, a paint trough, means for submerging in the paint therein kegs to be painted, including rotary clamping devices clamping the keg at the filling opening and the edge of the keg.

20 3. In combination, a paint trough, means for submerging in the paint therein kegs to be painted, including a spring-pressed, clamping device clamping the keg at the filling opening, and cam operated means for disengaging said device from said opening.

25 4. In combination, a paint trough, means for submerging in the paint therein kegs to be painted, including spring-pressed, clamping devices clamping the keg at the filling opening and the edge of the keg, and means for engaging and disengaging said devices from the above mentioned parts of the keg.

30 5. In combination, a paint trough, means for submerging in the paint therein kegs to be painted, including rotary clamping devices, and means for moving the kegs out of engagement with the clamping means.

35 6. In combination, a paint trough, means for submerging in the paint therein kegs to be painted, including rotary clamping devices clamping the keg at the filling opening, and means for moving the kegs out of engagement with the clamping means.

40 7. In combination, a paint trough, means for submerging in the paint therein kegs to be painted, including rotary clamping devices clamping the keg at the filling opening and the edge of the keg, and means for mov-

ing the kegs out of engagement with the clamping means.

8. In combination, a paint trough, means for submerging in the paint therein objects to be painted, a paint tank, means for supplying paint to the trough from the tank, and stirring means in the tank operated by the submerging means.

9. In combination, a paint trough, means for submerging in the paint therein kegs to be painted, including rotary clamping devices clamping the keg at the filling opening, a paint tank, means for supplying paint to the trough from the tank, and stirring means in the tank operated by the submerging means.

10. In combination, a paint trough, means for submerging in the paint therein objects to be painted, including rotary cradles, a paint tank, means for supplying paint to the trough from the tank, and stirring means in the tank operated by the submerging means.

11. A coating apparatus which includes a holding device for kegs comprising a bung registering with the filling opening, and means for maintaining said bung in engagement with said opening.

12. A coating apparatus which includes a holding device for kegs comprising a bung registering with the filling opening, and a device for clamping the opposite edge of the keg.

13. A holding device for kegs comprising a bung registering with the filling opening, and a pivoted arm having a notched head for clamping the opposite edge of the keg.

14. A holding device for kegs comprising a bung registering with the filling opening, and a pivoted, spring-pressed arm having a notched head for clamping the opposite edge of the keg.

In testimony that I claim the foregoing I have hereunto set my hand.

FLOYD D. STOWE.
